DESIGN FOR AN EYECUP

Saturnino Tofé Bonilla, New York, N. Y.

Application February 20, 1948, Serial No. 144,629

Term of patent 14 years

(Cl. D83—1)

To all whom it may concern:

Be it known that I, Saturnino Tofé Bonilla, a citizen of the Republic of Spain, residing at New York, in the county of New York and State of New York, have invented a new, original, and ornamental Design for an Eye Cup, of which the following is a specification, reference being had to the accompanying drawing, forming part thereof:

Figure 1 is a side elevation of an eye cup, showing my new design.

Figure 2 is a top plan view thereof, and

Figure 3 is a longitudinal section on the line 3—3 of Figure 2.

I claim:

The ornamental design for an eye cup, as shown.

SATURNINO TOFÉ BONILLA.
